UNITED STATES PATENT OFFICE

ALBERT N. EATON, OF OMAHA, NEBRASKA

SHEET-METAL GRAIN BIN

Application filed November 12, 1928. Serial No. 318,982.

The present invention relates to grain bin or corn crib, and more particularly to structures of this kind which are made of sheet metal and the like.

5 An object of the present invention is to provide a device of this character which is economical to manufacture, which may be made in sections and knocked down for shipment, and which may be readily assembled by the 10 user.

Another object of the invention is to provide a structure of this kind which may be made substantially wholly of sheet metal and to which access may be readily had for loading and unloading the same, and which is provided with a novel construction which admits of the complete and thorough ventilation of all parts of the bulk contained within the bin.

15 A further object of the invention is to provide a novel form of door or opening which extends throughout the height of the bin and which may be adjusted for closing the bin from the bottom upward as the grain, ears of corn or the like are stored in the bin, and to 20 provide a door structure which embodies 25 ventilating features capable of removal in sections or parts so that when the door is not in use for storing or removing the material with respect to the bin, the door may be utilized for ventilating purposes.

30 A more detailed object of the invention is to provide a door opening with a plurality of louvres or shutters which are removable so that when desired a selected number of the louvres may be removed from the door opening so that the user may walk erect into and 35 out of the bin for loading and unloading the same when only a relatively small quantity of grain or ears of corn are contained in the bin.

40 The invention also aims at the provision of a door closure which is constructed in a number of sections which may be adjusted relatively to each other and to the door opening 45 so as to open or close the upper, lower or intermediate portions of the door opening.

The above, and various other objects and advantages of this invention will be understood from, and set forth in the following 50 detailed description of the present preferred

embodiment, the same being illustrated in the accompanying drawings wherein:

Figure 1 is a perspective view of a grain bin or corn crib constructed according to the present invention.

55 Figure 2 is a detail enlarged sectional view of the upper extremity or ventilating portion of the bin.

Figure 3 is a fragmentary, enlarged, side elevation of the intermediate portions of the 60 ventilating pipe used.

Figure 4 is a top plan view of the bin, the upper portion thereof being broken away in part.

Figure 5 is a vertical section taken through 65 the door structure at one side of the bin, enlarged, showing the removable louvres or shutters employed, and

Figure 6 is an enlarged horizontal section 70 taken through the upper end of the door structure, showing the superposed cover plate for the door in the position of Figure 1.

Referring to the accompanying drawings for a more detailed explanation of the present embodiment of this invention, and wherein like parts are designated by similar numerals of reference throughout the several views, 10 designates a base strip or sheathing which is preferably of sheet metal and which is provided with any suitable number of ventilating 75 openings 11 through which air may enter into the lower end of the bin. The bin is provided with a base ring 12 to which the lower edge of the sheathing 10 may be secured, and a second ring 13 is secured to the upper edge of the sheathing 10. The sheathing 10 extends upwardly but a relatively short distance as compared with the height of the bin, and rising against the inner side of the sheathing 10, and extending upwardly therefrom are a number of studding strips 14 which may be interbraced by sway braces 15 crossed between adjacent studding strips 14 as shown in Figure 1.

90 One or more intermediate reinforcing rings 16 may be provided, and the same may be of angle or any other suitable construction adaptable to the bin. A top ring 17 is supported on the upper end of the studding 14, and the roof of the bin is secured to this top 95 100

ring 17. The roof comprises a plurality of segmental sections 18 having their adjacent edge portions secured together to form ridges 19 which reinforce the roof structure and 5 seal the sections 18 together.

The roof may be provided with any number of doors 20, one being shown in the present instance and the same comprising the lower end portion of one of the segmental 10 sections 18. The door is secured in position by hinges 21, as shown in Figure 4, and the outer end of the door is provided with a down-turned flange 22 which projects downwardly and outwardly to a sufficient extent 15 to cover the door structure hereinafter described and which is mounted in the side of the bin.

Disposed centrally and vertically within the bin is a ventilating tube 23 which extends 20 from the bottom of the bin upwardly through the top thereof. The ventilating tube 23 is provided in its side wall and for any suitable extent throughout the length of the tube 23, with a plurality of air openings or passages 25 24, as shown in Figures 1, 3 and 4, and these openings 24 may be provided by standing or pressing inwardly portions of the side wall of the tube 23. The tube 23 is adapted to ventilate the inner or middle portion of the 30 mass contained within the bin, when the bin is filled to a more or less extent.

As shown in Figures 1 and 2, the upper end of the ventilating tube 23 projects above the roof and is surmounted by a cap 25 of substantially conical form which is supported upon spaced upstanding braces or supports 26 secured to the adjacent sections of the roof. A retaining collar or ring 27 may be fitted about the upper end portion of the 40 ventilating tube 23 in position to overlap the upper edge of the roof and prevent moisture from entering beneath the same.

At one side of the bin, the latter is provided with a door opening which extends 45 throughout the entire height of the bin, and is preferably in line with the door 20. This door opening is defined between a pair of spaced apart and vertically disposed guide rails 28 to which the spaced ends of the 50 sheathing 10 are secured, and the entire structure above the sheathing 10 may be enclosed within a wall of wire meshing which terminate at the side rails 28. The guide rails 28 are of channel construction and are positioned with their flanges outturned away 55 from one another, and upon the outer flanges are mounted a plurality of cover plates or sections 30 which are adapted for adjustment into superposed relation, and which have 60 their ends overturned to provide flanges 31 which are so bent as to not only overlap one another but to also overlap the outer flanges of the guide rails 28. The cover plates are thus slidably mounted upon each other and 65 also upon the guide rails so that the cover

plates may be raised and lowered throughout the entire height of the door opening. Each cover plate 30 is provided at its lower end with an outturned reinforcing flange 32 for the purpose of reinforcing and bracing the plates. The cover plates 30 are of such size and number that the same may be slid one upon the other into position to entirely close the door opening from top to bottom of the bin, or may be collapsed or telescoped one upon the other at either the top of the bin, the intermediate portion of the bin, or at the bottom of the bin dependent upon the adjustment required. 70

The inner sides of the guide rails 28 are provided with pairs of registering cleats 33 which are secured across the guide rails 28 and which are also inclined inwardly and downwardly and disposed in pairs to provide guideways for the reception of the opposite edge portion of louvres or shutters 34. Each louvre or shutter 34 is in the form of a sheet metal plate of substantially the width of the guide groove thereof and which extends entirely across the door opening between the guide rails 28. The forward edge portions of the louvres 34 are provided with stop flanges 35 arranged to not only engage the forward edges of the adjacent cleats 33, but to also facilitate the sliding of the louvres 35 into and out of position.

In order to facilitate the loading of the bin or crib, such as when two wagonloads of corn or the like are adapted to be stored in the bin, the bin may be provided in one side remote 100 from the door 20, with an auxiliary door 36 which is located preferably near the top of the bin and supported upon vertical spaced rails or bars 37 which are incorporated in the body structure of the bin. This structure is 105 shown in Figure 4, and also in Figure 1.

When it is desired to load the bin, the main door opening, beneath the cover plates 30, may be utilized for the initial stages of the loading. In this case, the desired number of louvres 34 are removed from the guide rails 28 so that the person working in the loading operation may have free access to the interior of the bin and so that the person may walk 110 erect into and out of the bin. As soon, however, as the material accumulates in the bin to a point where it is necessary to close the lower end of the door, the louvre plates 34 are slid back into position, and other louvres are removed at an intermediate point throughout the height of the door. This operation is continued until the bin is filled to a substantial height when the cover plates 30 are shifted into lowered position to close the lower 115 end of the door opening and open the top of the door opening freely so that the material may be passed into the bin at its upper end. During this stage of the operation, not only the main door opening may be employed, but the auxiliary door 36 may be removed 120

from the side rails 37 so that a second filling operation may be carried on at an opposite side of the bin. When the bin is filled to a level near its top, the door 36 may be closed and also the cover plates 30 may be adjusted to completely close the side main opening, and the door 20 may then be opened to introduce the material into the space beneath the roof and in the top of the bin. The door 20 and its flange 22 are adapted to overlap the cover plates 30 so as to prevent moisture from entering through the main door opening.

In unloading the bin, the cover plates 30 may be slid into the position shown in Figure 1, and any number of the louvre plates 34 may be removed from the bottom of the bin so that access may be readily gained to the contents.

It is apparent that this bin or crib may be made in sections at the factory, may be shipped in packed down condition, and may be easily set up into position by the purchaser. If desired, a flooring 38 may be fitted in the lower end of the bin, or the bin may be erected directly on the ground. The louvre plates 34 are disposed at such an angle, and are so spaced apart, that the grain or other material which is contained within the bin will not be permitted to fall out through the main door opening when the cover plates 30 are raised, and at the same time the desired ventilation will be had to the material which covers the inner side of the door opening.

It is of course understood that various changes and modifications may be made in the details of design and construction of the above specifically described grain bin or corn crib to meet various conditions, without departing from the spirit of this invention, such changes and modifications being restricted only by the scope of the following claims.

What is claimed is—

1. In a grain crib, a container body having a vertically disposed door opening in one side thereof extending throughout substantially the entire height of the crib, and a plurality of door sections slidably mounted upon the side of said container body and arranged to slide in telescoping relation one section upon the other, whereby said door openings may be opened at either top, bottom or intermediate portions thereof.

2. In a grain crib, the combination of a body portion adapted to contain grain, said body portion having a vertically disposed door opening at one side extending throughout substantially the entire height of the crib, guide rails arranged at opposite sides of the door opening, a plurality of superposed cover plates slidably mounted one upon the other and upon said guide rails, said cover plates having overturned flanges at their opposite edges arranged for superposed engagement with each other and with said guide rails, said cover plates adapted for

adjustment one upon the other and upon said guide rails to selectively open the top, intermediate and bottom portions of said door openings.

3. In a grain crib, a body portion adapted to receive a quantity of grain and provided in one side with a vertically disposed door opening, adjustable closure sections for the door opening, and a plurality of removable louvres arranged in the door opening for normally closing the same to retain material in said body portion, said louvres being removable to admit free access into and from said body portion.

4. In a grain crib, a body portion adapted to receive grain, a pair of guide rails arranged vertically in spaced relation at one side of the body portion and defining a main door opening therein, a plurality of cover plates slidably mounted upon said guide rails adapted for adjustment to close said door opening, and a plurality of louvre plates slidably and detachably mounted in said opening upon the guide rails and disposed for selective removing from the door opening to admit positioning and removal of grain from within the body.

5. In a grain crib, the combination of a body portion adapted to receive grain, said body portion having a vertically disposed main door opening in one side, a pair of guide rails disposed at the opposite sides of said opening, a plurality of superposed cover plates slidably mounted upon one another and upon said guide rails, pairs of cleats arranged across the inner sides of said guide rails and inclined inwardly and downwardly with respect thereto, and louvre plates slidably mounted between said pairs of cleats for partially closing said main opening and for retaining material therein and admitting free access of air to the material, said louvre plates provided with downturned flanges at their outer edge portions adapted to engage said cleats for limiting the insertion of said louvre plates and admitting the easy removal thereof.

6. In a grain crib, a crib structure having a vertical opening, a frame disposed in the opening having pairs of guideways therein, spaced apart vertically and disposed diagonally, louvre vanes removably mounted in said guides, and a plurality of doors slidably upon said frame and upon one another and adapted to close the entire vertical opening.

In testimony whereof, I have affixed my signature.

ALBERT N. EATON.
